UNITED STATES PATENT OFFICE

2,291,133

CALCULATING MACHINE

Harold T. Avery, Oakland, Calif., assignor to
 Marchant Calculating Machine Company, a
 corporation of California

Original application December 18, 1933, Serial No.
 702,949. Divided and this application January
 15, 1940, Serial No. 313,918

14 Claims. (Cl. 235—63)

This invention relates to a machine having a shiftable carriage and has particular reference to a calculating machine of the type used to perform the cardinal calculations, including division and multiplication.

The invention is illustrated as embodied in a calculating machine of the type disclosed and claimed in Patent Number 2,211,736, issued August 13, 1940, on the copending application of Harold T. Avery, entitled "Calculating machines," Serial Number 702,949, filed December eighteenth, 1933, of which the present application is a division. Reference is hereby made to the above Avery patent for disclosure of a complete calculating machine including mechanisms not specifically described herein. It is to be understood, however, that although the invention is shown as applied to a machine of the general type disclosed in the above patent, the invention is also applicable to calculating machines of other types.

Calculating machines of the type referred to above usually have incorporated therein a stationary body portion and a laterally shiftable carriage thereon carrying the various calculation registering mechanisms. The carriage is shiftable either under automatic or manual control to different positions in order to enable the actuators, under control of certain selecting mechanism in the main body portion of the machine, to actuate different orders of the registering mechanism.

The principal object of the present invention is to provide a machine in which the carriage may be automatically shifted in either direction from any position to any other pre-selected position.

Another object is to provide improved setting and operating means for such carriage shifting mechanisms.

Another object is to provide a machine in which the carriage can be automatically traversed to a pre-selected position as an incident to the termination of a calculation operation, such as a division or multiplication operation.

Another object is to provide optional controls whereby the carriage may be moved to a pre-selected position, either under manual control at any time or automatically as an incident to the termination of a multiplication or division operation.

Another object is to provide means settable to indicate a given carriage position and means for later initiating movement of the carriage to the indicated position without disturbing the indi-

cating means, thereby obviating the necessity of resetting the indicating means if it is desired to again return the carriage to the indicated position.

5 Another object of the present invention is to provide improved means for shifting a carriage in either direction.

The machine of the present invention enables the operator to pre-select any of a number of carriage positions and thereafter, either on termination of a multiplication or division operation or on depressing a tabulator key, the carriage will automatically return to the pre-selected position. This operation obviates the necessity for the operator to direct his entire attention to the positioning of the carriage after one calculation and preparatory to the next calculation, as is necessary when the stopping of the carriage is determined by manual release of a shift key just as the carriage reaches its desired starting position. Thus, in a machine embodying the present invention, the operator will be free to prepare the various selecting and control keys for the next calculation while the carriage is being automatically moved to its predetermined starting position.

The manner in which the above and other objects of the invention are accomplished will be readily understood on reference to the following specification when read in conjunction with the accompanying drawings, wherein:

Figure 1 is a plan view of a calculating machine embodying the present invention and showing the keyboard, carriage, and the several controls.

35 Figure 2 is a sectional side elevation showing details of portions of the power operated mechanism utilized for shifting the carriage.

Figure 3 is a sectional view taken in part along the line 3—3 in Figure 2, showing the construction of the shift unit and its connection to the carriage.

40 Figures 4 and 5 illustrate details of the control mechanism for the shift unit.

Figure 6 is a sectional side elevation view illustrating the mechanism controlled by the tabulator key, and the carriage, for operating the carriage shifting mechanism.

Figure 7 is a sectional side elevation view taken through the forward portion of the machine and illustrating details of a portion of the tabulator controlling mechanism.

50 Figure 8 is a sectional view taken along the line 8—8 of Figure 7 and showing the connection between the tabulator key and certain parts of the tabulator control mechanism.

Figure 9 is a sectional view taken along the line 9—9 of Figure 7, showing a portion of the tabulator mechanism.

Figure 10 is a sectional plan view taken through a portion of the tabulator control mechanism.

Figure 11 illustrates the details of construction of the dial assembly associated with the tabulator control knob.

Figure 12 is a plan view, with parts broken away, showing a portion of the tabulator control mechanism in the frame of the machine, and the relation of this control mechanism to the carriage.

Figure 13 is a sectional side elevation view taken through the machine and illustrating the carriage dipping mechanism and certain mechanism utilized in connection with the shifting of the carriage.

Figure 14 illustrates certain details of the mechanism utilized in connection with the carriage dipping mechanism.

Figure 15 is a transverse sectional view through the carriage illustrating the mechanism for disconnecting the carriage from the carriage shifting mechanism.

Referring to Figure 1, the calculating machine is shown as comprising a keyboard having a number of aligned rows of numeral keys 100. The keys 100 determine the amount entered by the actuating mechanism into the different orders of an accumulator register 2318, provided in a shiftable carriage 250, in accordance with the numerical values of the particular keys 100 depressed.

Add and subtract bars 800 and 880, respectively, are provided for controlling such actuating mechanism (not shown) to add or subtract an amount set up in the various keys 100 to or from an amount set up in the register 2318, while a division key 970 is provided to control the actuating mechanism to divide an amount set up on the keys 100 into an amount appearing on the register 2318. A stop key 885 is provided for arresting the operation of the machine in automatic division whenever desired. A row of multiplier keys 2100 is arranged along the right hand side of the machine to control the actuator mechanism to multiply an amount set up on keys 100 by an amount corresponding to the numerical value of the particular multiplier key depressed.

The manner in which the above mentioned actuating mechanism is controlled by the various control keys is described in detail in the above mentioned patent. The keyboard also includes a tabulator key 1500 for initiating carriage movement to a position determined by the setting of a tabulator knob 1499, and a back space key 1405 for initiating, when depressed, a one step shift of the carriage to the right.

The carriage 250, in addition to its accumulator register 2318, comprises a pair of counter registers 1800 and 1801 aligned side by side, directly above the register 2318, for the purpose of counting the various machine cycles and thereby displaying the quotient in division operations and the multiplier in multiplication operations.

The carriage of the machine illustrated is movable in either direction to nine different positions. However, the number of positions may be increased or decreased as desired without affecting the mode of operation of the machine. The position of the carriage at any one time is indicated by a stationary pointer 1498 which, in the example illustrated in Figure 1, indicates 75 in the example illustrated in Figure 1, indicates

that the carriage is in the number "three" position.

The carriage is supported in the machine for transverse shifting in either direction by parallel shafts 259 and 260 (Figures 12 and 15) secured to opposite ends of the carriage and slideable in suitable bushings (not shown) positioned in stationary side frames on opposite sides of the machine.

Carriage shifting mechanism

Shifting of the carriage 250 is effected from a driving motor (not shown) by a shift mechanism illustrated in Figures 2 to 5, inclusive, under control of a control member 1300 rockable on a shaft 1301. Member 1300 is rocked either clockwise or counter-clockwise under manual or automatic control in a manner to be described later.

When member 1300 is moved clockwise, an extension 1302 thereon is positioned in engagement with a toothed wheel 1303 and the carriage is shifted to the right. When member 1300 is moved counter-clockwise, it positions a point 1304 thereon in engagement with a star wheel and the carriage is shifted to the left.

The engagement of the toothed wheel 1303 or of the wheel 1305 by the control member 1300 results in the selective turning of a carriage shifting shaft 334 by power transmitted through the following mechanism. A gear 362 (Figure 3) continuously rotated by the driving motor (not shown) whenever the motor circuit is closed, is secured to a shaft 1306 which is journaled in bearings provided in center and right side frames 524 and 510, respectively. A sleeve 1308, also secured to the shaft 1306, has mounted thereon a gear 648, driving certain related parts (not shown). A member 1307 is suitably fixed to the sleeve 1308 and has a pair of lugs formed thereon and extending into notches 1311 formed in the gear 648 to provide a driving connection between this gear and shaft 306.

A spider 1309 is secured to the gear 648 and sleeve 1308 by riveting over the end of sleeve 1308 upon which the spider 1309 is fixed. Spider 1309 has welded to one side thereof an internal ring gear 1315. This gear 1315 is in mesh with three planetary gears 1316, each riveted to one end of a respective shaft 1317, three such shafts being journaled in bearings 1318 equi-spaced from each other in a toothed wheel 1303. The planetary gears 1316 also mesh with a sun gear 1320 formed upon one end of a sleeve 1321, which is rotatably mounted on a reduced portion of the shaft 1306 and has the star wheel 1305 suitably secured thereto. Planetary gears 1322 are formed on the opposite ends of shafts 1317 and mesh with a sun gear 1327 rotatably mounted on the sleeve 1321, and secured to a gear 1324.

Gear 648 always rotates when the motor is rotating, so that the ring gear 1315 drives planetary gears 1316 and 1322, revolving them idly around gear 1327 which remains stationary, and driving gear 1320, sleeve 1321 and star wheel 1305 idly. If the toothed wheel 1303 is held, however, by extension 1302, revolution of the planetary gears 1316 and 1322 about gear 1327 is prevented and the planetary gears rotate about their own axes to rotate the sun gear 1327 and its associated gear 1324. In this case, sun gear 1320, sleeve 1321 and star wheel 1305 merely idle on shaft 1306. If, however, the star wheel 1305 is held by point 1304 of control member 1300, the sun gear 1320 will be held stationary and the plane-

tary gears 1316 and 1322 will both rotate about their own axes and revolve about the gear 1327 driving the gear 1324 in the opposite direction. This selective reversal of rotation of gear 1324 is utilized to effect a shift of the carriage in either direction.

A gear 1326 (Figure 3) is rotatably mounted on a hollow shaft 1331 between a cam 1332 (Figures 3 and 5) and a spacer 1330 keyed to said shaft. A sleeve 1333 (Figures 3 and 4) is also rotatably mounted on the hollow shaft and supports a cam 1334 thereon, while a centralizer disc 1335 is keyed to the hollow shaft 1331. A spring 1337 is compressed between a lock washer 1338 and lock nuts 1339 mounted on a threaded shaft 1336 which is screwed into the hollow shaft 1331. This construction provides for a friction drive connection between gear 1326 and shaft 1331 effected by cam 1332 and spacer 1330 which are keyed to shaft 1331 and pressed against the gear 1326 by spring 1337 bearing against the lock washer 1338, the centralizer disc 1335, the spacer 1333, and the cam 1332.

The hollow shaft 1331 is supported in a suitable bearing 1340 provided in the supporting plate 524 of the machine. A mitre gear 1341 is fixed on the end of the shaft 1331 and meshes with a mitre gear 1342 mounted on the lower end of the vertical shaft 334, rotatably supported in an angle piece 1343 secured to the base plate 2151 of the machine which also carries a sleeve bearing 1344 riveted to the angle piece, which bearing supports an end of the hollow shaft 1331.

A plate 333 is secured to the upper end of shaft 334 and has a pair of diametrically opposed rollers 332 mounted on the upper surface thereof. Rollers 332 mesh with the teeth of a comb 330 (Figures 3, 12, and 15) supported at the rear of the carriage 250 and thereby shift the carriage transversely on rotation of shaft 324.

It should be noted that the various teeth in comb 330 are spaced apart from each other a distance equal to the spacing between each of the nine different carriage positions. Thus, each half rotation of the shafts 334 and 1331 will shift the carriage from one operating position to the next. To enable manual shifting of the carriage independently of the shifting mechanism, the comb 330 is pivoted on a shaft 331 (Figure 15) and is rockable out of engagement with the rollers 332 on the plate 33. The comb 330 has a slot formed in a vertical wall thereof, into which slot a lug 339 formed on a lever 335 extends. The lever 335 is also pivoted on the shaft 331 and extends through a slot in the carriage cover, terminating in a handle 336. The lever 335 is normally held in a raised position against a stop pin 338 by a tension spring 337 so as to position the comb 330 in mesh with the rollers 332. However, when the handle is depressed by the operator the comb 330 is raised away from the rollers enabling the carriage to be moved sideways.

Spring means are provided to centralize the control member 1300 into the position shown in Figure 2, as will be described hereinafter, and, in order to maintain the member 1300 in displaced position until the carriage has been shifted a full step, once a shift is initiated, the following mechanism is provided.

A latch lever 1350 (Figure 2) is pivoted on a shaft 1351 and is urged in a clockwise direction by a tension spring 1352. When member 1300 is in its centralized position indicated in Figure 2, a projection 1353 on lever 1350 abuts an ear 1354 formed on the member 1300. However, when the

member is rocked clockwise or counter-clockwise to initiate a carriage shift, the projection 1353 will seat either under or above the ear 1354 on member 1300 and therefore latch that member in its displaced position.

Upon rotation of shaft 1331 (see also Figure 4), lever 1350 is moved by cam 1334 to release the ear 1354 at about the middle of the carriage shifting cycle. An arm 1356 is secured to a bushing 1345 pinned to shaft 1351 and includes an extension or nose 1357 engaging the periphery of cam 1334 so that when this cam rotates, the lever 1356 is moved in a counter-clockwise direction to engage an ear 1358 on lever 1350 and rock it to release extension 1354.

It is to be noted that the cam 1334 includes two opposite steep rises over which the nose 1357 rides. Upon clockwise rotation of the cam from the position shown in Figure 4, the nose 1357 rides over one of these rises at about the middle of the cycle, while, if counter-clockwise rotation of the cam 1334 took place, the arm 1356 would be moved a distance sufficient to release the ear 1358 early in the cycle. To secure the same cyclic time of operation of the lever 1350, regardless of the direction of carriage shift, the cam 1334 is free on the sleeve 1333, unaffected by spring 1337 which presses disc 1335 against the end of sleeve 1333, and is driven by the centralizer disc 1335 which is keyed to shaft 1331. As appears in Figure 2, this disc 1335 includes an elongated notch or depression 1360 in which a roller 1361 on cam 1334 is movable. Upon clockwise rotation of the centralizer disc 1335 from the position shown in Figure 2, roller 1361 on cam 1334 is engaged immediately by the adjacent edge of the notch 1360 and the cam 1334 is rotated. However, upon counter-clockwise rotation of the centralizer disc 1335, the roller 1361 is engaged by the opposite side of the notch 1360 of the disc 1335 only after the centralizer has rotated nearly half a revolution so that the rocking of the arm 1356 and disengagement of the ear 1354 occurs at the same cyclic time in each case.

The centralizer disc carries two rollers 1363 (Figure 2) against which an arm of bell crank 1364 bears under the pull of a spring 1364A so as to centralize the drive unit as well as the carriage proper at the end of a carriage shift, providing, of course, the member 1300 is centralized at this time.

To further aid in maintaining the control member 1300 in controlling position until just before the end of a carriage step or shift, a lever 1365 (Figures 2 and 5) is provided. Lever 1365 is also mounted upon the shaft 1351 and is pulled by spring 1366 in a counter-clockwise direction so that its tail 1367 rides against the periphery of cam 1332. This cam 1332, which is keyed to the hollow shaft 1331, serves to rock the point 1368 on the lever 1365 into and out of engagement with the shelf 1354, the point lying either above or below the shelf depending upon the direction of movement of the member 1300. The lever 1365 is moved in to hold the shelf 1354 just before the projection 1353 is pulled out and thus ensures that the clutch operation will continue. This lever 1365 is rocked out just before the end of each individual shift cycle so that member 1300 can be centralized to disengage the unit and the shift will end, unless the shift called for is a multi-order shift, in which event member 1300 will be held in its displaced position by other means hereinafter described.

The shifting mechanism is maintained in a neutral position when not called on to shift the carriage by the following mechanism. Referring to Figures 2 and 6, the control member 1300 is pivotally connected to a link 1374, the other end of which is pivoted to the upper end of a lever 1375 rockable about a shaft 1376. Lever 1375 is resiliently maintained in a centralized position, to maintain the control member 1300 in a centralized position, by a centralizing lever 1410 which is pivoted at 1411 on a stationary pin extending from the machine frame. Lever 1410 has an extension 1410a normally in engagement with lever 1375 above shaft 1376 and a lower offset portion 1410b normally in engagement with lever 1375 below shaft 1376. Lever 1410 is urged in a counter-clockwise direction by a spring 1408 tensioned between a stationary pin 1401 and an ear 1402 on the lever 1410 so as to hold the lever 1375 in the position shown in Figure 6 whenever the various shift controlling mechanisms to be described hereinafter are not in operative positions. The lever 1410 is also provided with extending fingers 1415 which lie on opposite sides of lever 1375 and act as guides.

TABULATING CARRIAGE SHIFT CONTROLLING MECHANISM

Direction control

The details of the mechanism for controlling the direction and extent to which the carriage moves upon depression of the tabulating key 1500, or at the end of a division or multiplication operation, will now be described. As appears in Figure 12, a Geneva cross 1520 is mounted on a shaft 1521 journaled in a bracket 1522 on the left side frame 523 of the machine. Shaft 1521 is connected by a flexible spring coupling 1523 to a shaft 1524 likewise journaled in brackets 1525 on the side frame. Rotation of the shaft 1524 is transmitted through another flexible coupling 1526 to an angularly positioned shaft 1527 journaled in brackets 1528 on the side frame and bottom frame 2151 of the machine to another flexible connection 1529 which is connected to a stub shaft 1530 (Figure 10) journaled in a bearing 1534 on a vertical flange 1540 of the bottom frame 2151 of the machine. A gear 1531 is secured to stub shaft 1530. The several flexible couplings are formed of springs wound over each other in opposite directions and inserted into the shafts to which they are joined and wherein they are secured by set screws and sweating.

The Geneva cross 1520 (Figure 12) engages a rack 1532 which is fixed to the carriage along the left hand rear side thereof, each step of movement of the carriage from one position to the next causing a ninety degree rotation of the Geneva cross. This results in a quarter rotation of the gear 1531 and its shaft 1530 (see also Figure 10) in the supporting bearing 1534. Rotation of gear 1531 also rotates a gear 1536 meshing therewith, which is fixed to a sun gear 1537 (Figure 10) formed on a shaft 1538. This shaft 1538 is journaled at one end in a member 1539 riveted to the flange 1540 and at the other end in one end of a shaft 1541. Rotation of the sun gear 1537 causes rotation of dual planetary gears 1542 and 1543 to rotate a ring gear 1544, revolution of the planetary gear support being prevented except during manual setting. The planetary gears are disposed on opposite ends of a shaft journaled in a plate 1545, secured on shaft 1541, rotatably mounted in a supporting bearing 1546 so that it can be set to any desired position by knob 1499, 75

which is utilized to predetermine the position to which the carriage is to return, but will otherwise remain fixed.

The ring gear 1544 is secured to a spider 1548 (see also Figure 9) having an extension 1549. This extension is provided with a pin 1550 which, as the spider is rotated, moves around the inner periphery of a member 1551, pivotally mounted by means of stud 1553 in bushing in front frame member 2161.

In that position shown in Figure 9, the pin 1550 is seated in a notch 1552 in member 1551, this position corresponding to that which the parts occupy when the carriage is in the position corresponding to the carriage position indicated by the setting of knob 1499.

As shown in Figures 10 and 11, the knob 1499 is fixed to shaft 1541 and is manually adjustable into nine different rotational positions. For the purpose of holding shaft 1541 in any selected position a ratchet member 1564, keyed to shaft 1541, is engaged by a roller 1563 mounted on a lever 1561, pivoted at 1562 to the frame member 2161. Roller 1563 is pulled into any one of nine equi-spaced notches in member 1564 by a spring 1565 to hold the shaft in any adjusted position. A dial 1560 keyed to shaft 1541 carries numerals 1566, visible through an opening 1561 (Figure 1) in the cover 115 of the machine so that the setting of the tabulator may be readily noted.

The mechanism whereby the knob 1499 revolves the planetary gears 1542 and 1543 to any of a series of radial stations about shaft 1541 constitutes a means for forming a series of mechanical representations corresponding to the respective positions of the carriage, because in each of the radial positions, or stations, to which these gears may be set, the mechanism controlled thereby will cause the carriage to be arrested when it reaches a different position corresponding to the setting of the gear positioning mechanism.

From the above it will be readily understood that the pin 1550 will be differentially moved to either side of its position shown in Figure 9 in accordance with both the carriage position at any one time and the setting of knob 1499. Thus, when the carriage 250 moves to the left of a position indicated by the setting of knob 1499, the pin 1550 rocks out of notch 1552 and in a counter-clockwise direction about shaft 1541. This motion of pin 1550 causes it to rise against the upper inner periphery of lever member 1551 and thus cause that member to rock clockwise on its supporting stud 1553. Likewise, when the carriage 250 moves to the right of a position indicated by the setting of knob 1499, the pin 1550 will cause the lever member to rock counter-clockwise from the position shown in Figure 9.

The tail of member 1551 is bifurcated (Figure 9) to receive one end of a lever 1554 pivotally supported on a pin 1555 (Figure 7) and which carries a stud 1556 lying in a slot in a lever 1510. Lever 1510 is rockable about a shaft 1511 to either side of the medial position shown in Figure 7 and forms a direction control member to determine the direction of the carriage shift when such takes place. That is, the lever 1510 is positioned on one side or the other of its medial position depending on whether the position of the carriage is to one side or the other of the carriage position indicated by the knob 1499.

Member 1510 has a T-shaped slot 1512 therein, the lowermost portion or stem of which is disposed substantially vertically when the member is in its medial position. A pin 1513, mounted

on a link 1519 pivoted at 1487 to a link 1508 free on a shaft 1478, extends into the slot 1512 and normally rides in the upper portion thereof when the tabulator shift is inoperative due to a spring 1558 which raises the forward end of link 1519. On initiation of operation of the tabulator shift in a manner hereinafter described, the pin 1513 is forced into the stem of the T-slot 1512 and, therefore, the link 1519 is moved to the left or to the right, as viewed in Figure 7, depending on the position of lever 1510 at that time.

Such movement of link 1519 initiates operation of the carriage shifting mechanism to shift the carriage in one direction or the other according to the direction of movement of said link. Referring to Figures 6 and 7, a link 1473 is also pivotally connected at one end thereof to the pin 1487 and has a notch 1474 at the other end thereof, normally held in engagement with the lower end of the carriage shift lever 1375 (previously described in connection with the carriage shifting mechanism) by means of a link 1476 pivotally connected between link 1473 and a bell crank 1026 supported on a shaft 976. Thus, if the lever 1510 is positioned clockwise of its medial position when the tabulating shift operation is started by depressing the forward end of link 1519, the shift control lever 1300 will likewise be moved clockwise to institute a shift of the carriage to the right, and if lever 1510 is positioned counter-clockwise of its medial position at such time a shift to the left will be instituted.

Actuation

Actuation of the tabulating carriage shift controlling mechanism to cause the carriage 250 to be shifted to the left or right to any position determined by the setting of knob 1499 may be effected either manually by depression of the tabulating key 1500 or automatically as an incident to the termination of a multiplication or division operation when the carriage is moved to its left-most position.

Describing first the manual actuation of the tabulating shift controls, the tabulator key 1500 (Figure 6) is mounted upon a stem 1501 supported by a pin 1502 in a slot in the key stem and by a lever 1503 pinned to a shaft 1478 (Figures 6, 7, and 8) to which it is pivotally connected. and the right side frame 610 and carries there. This shaft extends through the center frame 524 and the right side frame 610 and carries thereon, adjacent the center frame, a member 1504 (Figure 7) which is pinned to the shaft. Freely supported upon the shaft 1478, adjacent member 1504, is a member 1477 provided with a tail 1505 carrying a roller 1506 overlying lever 1519. The member 1504 and the member 1477, respectively, include noses extending toward each other and retaining a strong compression spring 1507. Member 1504 includes a shelf 1508 which extends beneath the tail 1505 to prevent over extension of the spring 1507. Movement of member 1504 by shaft 1478 is transmitted to the member 1477 through the spring 1507 so that the roller 1506 will be depressed upon depression of the tabulator key 1500 rocking lever 1519 on pivot 1487 to depress the pin 1513 of lever 1519 into the stem of the T-slot 1512 in lever 1510 and thus institute the carriage shift.

Means are provided for latching the parts in this position to maintain the shifting mechanism in operation even though the operator may remove his finger from the key 1500. The lever 1510 includes an extension 1514 carrying a pin

1515 which engages a nose 1516 on the lever 1517. Lever 1517 is pivotally supported by a pin 1518 and is pulled by a spring so that its nose 1516 engages the pin 1515. Depending upon whether the carriage is to the left or to the right of the desired position, the pin 1515 will lie either above or below the nose 1516 or, if the carriage is in the position called for by the tabulating setting mechanism, it will stand against the nose as appears in Figure 7. If the pin 1515 is above the nose 1516, the pin 1513 will ride down the left hand side of the T-shaped slot 1512 upon depression of the key 1500 and the link 1473 will be moved to the right. If the pin 1515 is below the nose 1516, the pin 1513 will ride down the right hand side of the notch 1512 and the link 1473 will be moved to the left as is shown in Figure 7.

In either case, the latch end of lever 1517 will be pulled into engagement with the upper side of the stud which carries the roller 1506, thereby holding the tail 1505 and lever 1519 depressed. Movement of the carriage thus initiated carries it toward a position corresponding to the setting of knob 1499, and operation of the shifting mechanism is automatically terminated when the carriage arrives in that position. Pin 1550 (Figure 9) is returned toward notch 1552 in member 1551 by such carriage movement, and when the pin enters this notch it tends to return member 1551 to the medial position in which the latter is shown in Figure 9, although the entire linkage comprising member 1551, lever 1554, lever 1510 (Figure 7), lever 1519, link 1473, lever 1375 (Figure 6) and link 1374 will be held displaced until near the end of the current shift cycle by the shift control member 1300 which is held in displaced position until the end of the shift cycle by the levers 1365 and 1366 as previously described. At approximately the end of the current shift cycle, however, levers 1365 and 1366 release member 1300, and centralizer 1410 pulled by spring 1400 returns the entire linkage system described above, as well as member 1300, to medial position, terminating operation of the shift mechanism.

When lever 1510 returns to its medial position shown in Figure 7, due to the movement of the carriage 250 into a position corresponding to the indicated carriage position of knob 1499, the pin 1515 thereon will rock lever 1517 to release the stud on which roller 1506 is mounted. Retraction of roller 1506 enables the tabulator key 1500 to be raised by its spring 1501a to its inoperative position.

The automatic initiation of the tabulating shift mechanism as an incident to termination of a multiplication or division calculation operation will now be described.

Normally, during division and multiplication operations, except when the carriage is in its extreme left end position, an automatic shift of the carriage one step to the left is instituted at the completion of the calculation in the particular order in which the carriage is positioned. To accomplish this a link 1377 (Figure 6) is provided which is moved to the left of the position shown in Figure 6 as an incident to the termination of a calculation operation in the particular order in which the carriage is positioned. Movement of link 1377 may be accomplished by any means operated as an incident to termination of a division or multiplication operation in each order. I prefer, however, to employ the

means disclosed in detail in the above Avery application and which will be described hereinafter. Link 1377 has an upwardly turned end 1378, a downwardly turned end 1380, and is pivotally mounted intermediately by a pin 1379 on a lever 1380. The lever 1380 is pivotally supported on a shaft 1381 mounted in the frame of the machine while a spring 1382 is provided between an extension of the lever 1380 and link 1377 to pull the link 1377 counter-clockwise. Lever 1380 is pivoted at the upper end thereof to a dog 1383 having a shoulder formed thereon which is normally in engagement with an ear 1384 on the link 1374, except when the carriage is in its left end position. The dog 1383 has an elongated slot 1576 therein which rides over a pin 1574 formed on an arm of a lever 1572, pivotally mounted in the frame of the machine, which lever is normally held in the position illustrated in Figure 6, except when the carriage is in its left end position.

The right hand end of link 1377 has the nose 1385 thereof normally positioned below and against an extension 1386 of an actuating member for moving the link 1377.

At the beginning of the division or multiplication operation in any one particular carriage order the extension 1386 is moved to the right enabling the spring 1382 to position the nose 1385 of link 1377 against the left hand edge of this extension 1386. At the end of the operation in the particular carriage order the extension 1386 moves to the left to likewise move link 1377 to the left and, since the dog 1383 is in engagement with the ear 1384 of link 1374, the shift control member 1300 will be rocked counter-clockwise through the link 1374 and thus engage its point 1304 with the star wheel 1305 (Figure 2) of the carriage shifting mechanism and start a shift to the left. To insure a single step of movement of the carriage the link 1377 is rocked clockwise against the action of the spring 1382 by suitable means (to be described later) during the shifting operation and thereby move the nose 1385 of link 1377 under the extension 1386 as shown in Figure 6.

As the carriage is shifted into its left end position a nose 1570 (Figure 6) on the right hand end of carriage 250 engages a beveled nose 1571 on lever 1572 to rock that lever in a counter-clockwise direction about its supporting shaft 1569 against the tension of spring 1573. The counter-clockwise rotation of lever 1572 raises the dog 1383 to remove the bottom shoulder thereof from against ear 1384 on link 1374 and bring an upper shoulder 1577 of dog 1383 into engagement with a shelf 1578 on a lever 1579 pinned to a shaft 1580. Thereafter, on leftward movement of extension 1386 as an incident to the termination of the calculation in the last carriage order (as described hereinbefore) dog 1383 is rocked to shift the lever 1579 to the left so that shaft 1580 is rocked in a clockwise direction. This results in clockwise movement of a lever 1581 also pinned to shaft 1580 and a movement to the left in Figure 6 of a link 1582 against the pull of a spring 1583. Link 1582 is connected by a pin and slot connection 1584 to a lever 1585 pinned to shaft 1478, as appears in Figure 8, so that the shaft 1478 is rocked and the same action instituted as if the tabulating key 1500 had been depressed. This results in the carriage being moved to that position determined by the tabulating setting mechanism.

AUTOMATIC CARRIAGE SHIFT CONTROL DURING DIVISION AND MULTIPLICATION

As described hereinbefore, the carriage shift initiating link 1377 (Figure 6) is moved to the left as an incident to the termination of a division or multiplication operation in each carriage position so as to move the dog 1383 leftward and thereby institute either a carriage shift to the left or actuation of the tabulating shift control mechanism depending on the position of the carriage 250.

Although any means may be employed to actuate link 1377 the following mechanism, disclosed in the above Avery application, is preferably employed.

Referring to Figure 13, the carriage has a series of aligned plates, one of which is shown at 266, all connected at their rear ends to a bail 269 and supported at their forward ends for pivotal movement on a shaft 262. Three shafts 270, 272, and 320 are supported by the plates 266 and form part of the accumulator register 2318. A pair of gears 273 and 274, meshing with each other, are mounted on the shafts 270 and 272, respectively, in each order of the register, each gear 273 driving a respective dial shell 279. A pawl 319, rockably mounted on shaft 320, is provided in each order and is urged by a spring 318 into engagement with the teeth of the respective gear 271 to hold that gear stationary whenever it is not actuated by an actuator gear 189. Each shell 279 has a series of numerals from "zero" to "nine" spaced around the periphery thereof, one of which is always visible through an opening formed in the cover of the carriage 250. The various dial shells in the different orders of the register 2318 are connected together through suitable tens-carrying mechanism (not shown).

At the beginning of a calculation operation, such as multiplication or division, the bail 269 is dipped to mesh the gears 271 with respective actuator gears 189 which are mounted on sleeves 169 journaled on a shaft 170. Thereafter, the actuator gears 189 are rotated differential amounts in a manner described in the above mentioned application. After the conclusion of rotation of the gears 189, the gears 271, having transmitted a certain rotation to the dial shells 279, are raised out of mesh with gears 189, and, in the case of multiplication or division, the carriage is automatically shifted to the left one step preparatory to continuation of the problem.

The means for dipping the carriage, from that position in which it appears in Figure 13, to bring gears 271 into mesh with gears 189 and then elevate the carriage at completion of the calculation in the particular carriage position comprise vertical sliding links, one of which is shown at 566, slidable over pins 567 on opposite sides of the machine. Each link is provided with rollers 568 engaging bail 269, the links being biased upwardly by a spring 569. Links 566 are hinged to cam levers 570 and 571 by pins 572. The cam levers 570 are rockable on a shaft 225 and carry rollers 573 in engagement with cams 574 keyed on a shaft 431 so that the links 566 are positively pulled down by rotation of shaft 431.

Means are provided for latching the carriage in raised position when the accumulator is not in operation and during shifting operations, and for latching the carriage in its lower position during engagement of gears 271 and 189. This means includes a latch lever 575 in the form of a bell crank pivoted at 576 and having a nose 577 formed at the upper end thereof to engage the

lower edge of lateral extensions 578 on cam levers 570 and 571. The latch levers are urged to engage the extensions 578 by a spring 579, and are normally effective to maintain the carriage in its raised position.

To disengage the latch levers 575 and permit lowering of the carriage upon beginning of a setting clutch operation (not shown) preparatory to a calculation operation, as well as to latch the carriage in its lower position, means are provided to move levers 575 and so rock their noses 577 out of engagement with the lower edges of extensions 578, and back into engagement with the upper edges thereof. A lever 580 is secured to a shaft 581 in position to be engaged by an extension 582 on a plate indicated by dot-dash lines 552 rockable on shaft 225 (Figure 13) so that rocking of plate 552 by reverse cams 550 and 551, keyed on shaft 431, also rocks shaft 581, to which rocking arms 583 and 584 are attached. Arm 583 is connected to levers 575 by pivotal connections 585 so that when the levers are thus rocked, the links 566 are not held by noses 577, and cams 574 may then lower the plates 266 to engage the gears 271 with the actuator gears 189. As the gears 271 are moved into mesh with the gears 189, cams 550 and 551, by rocking plate 552 permit springs 579 to pull the latch levers 575 counter-clockwise to reengage noses 577 over extensions 578.

Pawl 201, normally in engagement with the gears 189 when the gears 271 are raised, are released from the blocking of gears 189 when gears 271 are lowered. Pawls 201 are keyed on a shaft 202 to which is also keyed a lever 586 slotted to receive a pin 587 provided on an upwardly extending arm 588 formed on the rocking cam lever 510. As an incident to termination of rotation of the various actuator gears 189, a sleeve 594, rotatably mounted on a shaft 595 is rotated by a "restore clutch" 700. A cam 593 (Figure 14) secured on the sleeve 594 is thus rotated. This cam rocks a lever 591 clockwise about a shaft 598 to move lever 584 and so rock shaft 581 and levers 575 to release the latched-down carriage.

The sleeve 594 carries another cam 596 (Figure 13) which is employed to prevent the carriage from rising too rapidly. A lever 597, hinged on a shaft 598, bears against cam 596 and against a lever 599 keyed to a shaft 600. Levers 601 are also keyed to this shaft and joined by pin and slot connections 602 to the links 566 so that the rate of rise of the links 566 under the pull of spring 569 is no greater than that permitted by cam 596.

As the cam lever 570 is rocked counter-clockwise due to raising of the links 566 as an incident to the termination of the calculation in the particular carriage order, the extension 1386 on lever 570, which extension is now to the right of the nose 1385 of link 1377, will engage that link and shift it to the left, thereby instituting a shift of the carriage 250 to the left unless it is in its leftmost position.

To ensure that the carriage shift is limited to a single step, lever 1377 is rocked clockwise and is disengaged from extension 1386, during the carriage shift. It will be recalled that during the carriage shift operation cycle, cam 1334 operates to move lever 1356 (Figures 4 and 6) in a counter-clockwise direction to remove lever 1350 from engagement with extension 1354 on the shift control member 1300. Movement of the lever 1356 also rocks a bell crank indicated by the dot-dash lines 1387 (Figure 6) clockwise about a shaft 1388 so that a shelf 1389 thereon, which lies beneath

the link 1377, rocks link 1377 clockwise about the pin 1379 to release its nose 1385 from extension 1386. The shift control member 1300 is thus freed from the restraint of extension 1386 and can be released and centralized at the end of a single cycle of operation. During the first cycle of operation of the shifting mechanism, in the course of an automatically initiated tabulation operation, the same mechanism frees member 1377 from lug 1386 to permit key 1500 to rise at the end of the operation.

I claim:

1. In a machine of the class described having a frame, a carriage transversely shiftable thereon to any of a series of operating positions, and motor driven means for shifting said carriage; the combination of carriage position mechanism including a member settable in synchronism with said carriage to a position corresponding to the position occupied by said carriage; tabulation control means including devices settable to any of a series of positions, each position corresponding to one of the respective operating positions of the carriage; direction control means including an element selectively settable jointly by said member and said devices upon setting movements of said carriage position mechanism and said tabulation control means or either of them, to control the direction of operation of said carriage shifting mechanism; and means controlled by said element, and operable after the same has been selectively set, for selectively initiating operation of said carriage shifting mechanism to cause shifting of the carriage in one direction or the other in accordance with the setting of said element.

2. In a machine of the class described having a frame, a carriage transversely shiftable thereon to any of a series of operating positions, and motor driven means for shifting said carriage; the combination of carriage position mechanism including a member settable in synchronism with said carriage to a position corresponding to the position occupied by said carriage; tabulation control means including mechanism manually settable to indicate any of a series of operating positions of said carriage, and devices adjustable by said mechanism to correspondence with such indication; direction control means including an element selectively settable jointly by said member and said devices upon setting movements of said carriage position mechanism and said tabulation control means or either of them, to control the direction of operation of said carriage shifting mechanism; and means controlled by said element, and operable after the same has been selectively set, for selectively initiating operation of said carriage shifting mechanism to cause shifting of the carriage in one direction or the other in accordance with the setting of said element.

3. In a machine of the class described having a frame, a carriage transversely shiftable thereon to any of a series of operating positions, and motor driven means for shifting said carriage; the combination of carriage position mechanism including a member settable in synchronism with said carriage to a position corresponding to the position occupied by said carriage; tabulation control means including devices settable to any of a series of positions, each position corresponding to one of the respective operating positions of the carriage; direction control means including an element selectively settable jointly by said member and said devices upon setting move-

ments of said carriage position mechanism and said tabulation control means or either of them, to control the direction of operation of said carriage shifting mechanism; means controlled by said element, and operable after the same has been selectively set, for selectively initiating operation of said carriage shifting mechanism to cause shifting of the carriage in one direction or the other in accordance with the setting of said element, and means responsive to said member and devices upon adjustment thereof to correspondence, for arresting operation of said carriage shifting mechanism.

4. In a machine of the class described having a frame, a carriage transversely shiftable thereon to any of a series of operating positions, and motor driven means for shifting said carriage; the combination of carriage position mechanism including a member settable in synchronism with said carriage to a position corresponding to the position occupied by said carriage; tabulation control means including devices settable to any of a series of positions, each position corresponding to one of the respective operating positions of the carriage; direction control means including an element selectively settable jointly by said member and said devices upon setting movements of said carriage position mechanism and said tabulation control means or either of them, to control the direction of operation of said carriage shifting mechanism; means controlled by said element, and operable after the same has been selectively set, for selectively initiating operation of said carriage shifting mechanism to cause shifting of the carriage in one direction or the other in accordance with the setting of said element, and means responsive to said direction control means for arresting operation of said carriage shifting mechanism.

5. In a machine of the class described having a frame, a carriage transversely shiftable thereon to any of a series of operating positions, and motor driven means for shifting said carriage; the combination of carriage position mechanism including a member settable in synchronism with said carriage to a position corresponding to the position occupied by said carriage; tabulation control means including devices settable to any of a series of positions, each position corresponding to one of the respective operating positions of the carriage; direction control means including an element selectively settable jointly by said member and said devices upon setting movements of said carriage position mechanism and said tabulation control means or either of them, to control the direction of operation of said carriage shifting mechanism; means controlled by said element, and operable after the same has been selectively set, for selectively initiating operation of said carriage shifting mechanism to cause shifting of the carriage in one direction or the other in accordance with the setting of said element, latch means for maintaining said carriage shifting mechanism in operation after initiation of the operation thereof, and means responsive to said member and said devices upon adjustment thereof to correspondence, for rendering said latch means ineffective.

6. In a machine of the class described having a frame, a carriage transversely shiftable thereon to any of a series of operating positions, and motor driven means for shifting said carriage; the combination of carriage position mechanism including a member settable in synchronism with

said carriage to a position corresponding to the position occupied by said carriage; tabulation control means including devices settable to any of a series of positions, each position corresponding to one of the respective operating positions of the carriage; direction control means including an element selectively settable jointly by said member and said devices upon setting movements of said carriage position mechanism and said tabulation control means or either of them, to control the direction of operation of said carriage shifting mechanism; means controlled by said element, and operable after the same has been selectively set, for selectively initiating operation of said carriage shifting mechanism to cause shifting of the carriage in one direction or the other in accordance with the setting of said element, latch means for maintaining said carriage shifting mechanism in operation after initiation of the operation thereof, and means responsive to said direction control means for rendering said latch means ineffective.

7. In a machine of the class described having a frame, a carriage transversely shiftable thereon to any of a series of operating positions, and motor driven means for shifting said carriage; the combination of carriage position mechanism including a member settable in synchronism with said carriage to a position corresponding to the position occupied by said carriage; tabulation control means including mechanism manually settable to indicate any of a series of operating positions of said carriage, and devices adjustable by said mechanism to correspondence with such indication; direction control means including an element selectively settable jointly by said member and said devices upon setting movements of said carriage position mechanism and said tabulation control means or either of them, to control the direction of operation of said carriage shifting mechanism; means controlled by said element, and operable after the same has been selectively set, for selectively initiating operation of said carriage shifting mechanism to cause shifting of the carriage in one direction or the other in accordance with the setting of said element, and means responsive to said member and devices upon adjustment thereof to correspondence, for arresting operation of said carriage shifting mechanism.

8. In a machine of the class described having a frame, a carriage transversely shiftable thereon to any of a series of operating positions, and motor driven means for shifting said carriage; the combination of carriage position mechanism including a member settable in synchronism with said carriage to a position corresponding to the position occupied by said carriage; tabulation control means including mechanism manually settable to indicate any of a series of operating positions of said carriage, and devices adjustable by said mechanism to correspondence with such indication; direction control means including an element selectively settable jointly by said member and said devices upon setting movements of said carriage position mechanism and said tabulation control means or either of them, to control the direction of operation of said carriage shifting mechanism; means controlled by said element, and operable after the same has been selectively set, for selectively initiating operation of said carriage shifting mechanism to cause shifting of the carriage in one direction or the other in accordance with the setting of said

element, and means responsive to said direction control means for arresting operation of said carriage shifting mechanism.

9. In a machine of the class described having a frame, a carriage transversely shiftable thereon to any of a series of operating positions, and motor driven means for shifting said carriage; the combination of carriage position mechanism including a member settable in synchronism with said carriage to a position corresponding to the position occupied by said carriage; tabulation control means including mechanism manually settable to indicate any of a series of operating positions of said carriage, and devices adjustable by said mechanism to correspondence with such indication; direction control means including an element selectively settable jointly by said member and said devices upon setting movements of said carriage position mechanism and said tabulation control means or either of them, to control the direction of operation of said carriage shifting mechanism; means controlled by said element, and operable after the same has been selectively set, for selectively initiating operation of said carriage shifting mechanism to cause shifting of the carriage in one direction or the other in accordance with the setting of said element, latch means for maintaining said carriage shifting mechanism in operation after initiation of the operation thereof, and means responsive to said member and said devices upon adjustment thereof to correspondence, for rendering said latch means ineffective.

10. In a machine of the class described having a frame, a carriage transversely shiftable thereon to any of a series of operating positions, and motor driven means for shifting said carriage; the combination of carriage position mechanism including a member settable in synchronism with said carriage to a position corresponding to the position occupied by said carriage; tabulation control means including mechanism manually settable to indicate any of a series of operating positions of said carriage, and devices adjustable by said mechanism to correspondence with such indication; direction control means including an element selectively settable jointly by said member and said devices upon setting movements of said carriage position mechanism and said tabulation control means or either of them, to control the direction of operation of said carriage shifting mechanism; means controlled by said element, and operable after the same has been selectively set, for selectively initiating operation of said carriage shifting mechanism to cause shifting of the carriage in one direction or the other in accordance with the setting of said element, latch means for maintaining said carriage shifting mechanism in operation after initiation of the operation thereof, and means responsive to said direction control means for rendering said latch means ineffective.

11. In a motor driven calculating machine having a carriage transversely shiftable to any of a series of operating positions, cyclically operable motor driven mechanism operable to shift said carriage between adjacent operating positions thereof, and division control devices for automatically controlling said machine in division computations comprising a manually operable member for initiating the operation, and means for terminating the operation; means for automatically controlling operation of said carriage shifting mechanism as an incident to the com-

pletion of said division operation comprising the combination of means controlled by said division terminating means upon operation thereof for initiating operation of said carriage shifting mechanism, said last mentioned means including a settable member movable to a set position by said division terminating means upon operation thereof; spring means for moving said member from set position to interrupt the operation of said carriage shifting mechanism at the conclusion of any cycle of operation thereof, holding means for preventing operation of said spring means, and means controlled by said carriage for releasing said spring means from restraint of said holding means.

12. In a motor driven calculating machine having a carriage transversely shiftable to any of a series of operating positions, cyclically operable motor driven mechanism operable to shift said carriage between adjacent operating positions thereof, and division control devices for automatically controlling said machine in division computation comprising a manually operable member for initiating the operation, and means for terminating the operation; means for automatically controlling operation of said carriage shifting mechanism as an incident to the completion of said division operation including the combination of means controlled by said division terminating means upon operation thereof for initiating operation of said carriage shifting mechanism, said last mentioned means including a settable member movable to a set position by said division terminating means upon operation thereof; spring means for moving said member from set position to interrupt the operation of said carriage shifting mechanism at the conclusion of any cycle of operation thereof, holding means for preventing operation of said spring means, means selectively adjustable to form a mechanical representation corresponding to any of the respective operating positions of said carriage, and means jointly controlled by the carriage and said selectively adjustable means for releasing said spring means from the restraint of said holding means.

13. In a motor driven calculating machine having a carriage transversely shiftable to any of a series of operating positions, cyclically operable motor driven mechanism reversibly operable to shift said carriage in either direction between adjacent operating positions thereof, means for initiating operation of said carriage shifting mechanism including a connecting member movable to either of two settings to control operation of said carriage shifting mechanism to shift said carriage in either direction, means normally positioning said member in one of said settings to control operation of said carriage shifting mechanism to shift said carriage in one direction, and division control devices for automatically controlling said machine in a division computation comprising a manually operable member for initiating the operation, means for operating said carriage shift initiating means, and means for terminating the division operation; means for automatically controlling operation of said carriage shifting mechanism to shift said carriage in the opposite direction as an incident to said division operation comprising the combination of means for initiating operation of said carriage shifting mechanism to shift the carriage in the opposite direction including a settable member movable to set position, means including said settable connecting member movable to the other

of said settings thereof for moving said settable member to set position, said settable connecting member being movable into the other of said settings by said division terminating mechanism upon operation thereof; spring means for moving said settable member from set position to interrupt the operation of said carriage shifting mechanism at the conclusion of any cycle of operation thereof, holding means for preventing operation of said spring means, and means controlled by said carriage for releasing said spring means from restraint of said holding means.

14. In a motor driven calculating machine having a carriage transversely shiftable to any of a series of operating positions, cyclically operable motor driven mechanism reversibly operable to shift said carriage in either direction between adjacent operating positions thereof, means for initiating operation of the carriage shifting mechanism including a connecting member movable to either of two settings to control operation of said carriage shifting mechanism to shift said carriage in either direction, means normally positioning said member in one of said settings to control operation of said carriage shifting mechanism to shift said carriage in one direction, and division control devices for automatically controlling said machine in its division computation comprising a manually operable member for initiating the operation, means for operating said

carriage shift initiating means, and means for terminating the division operation; means for automatically controlling operation of said carriage shifting mechanism to shift said carriage in the opposite direction as an incident to said division operation comprising the combination of means for initiating operation of said carriage shifting mechanism to shift the carriage in opposite direction including a settable member movable to set position, means including said settable connecting member movable to the other of said settings thereof for moving said settable member to set position, said settable connecting member being movable into the other of said settings by said division terminating mechanism upon operation thereof; spring means for moving said settable member from set position to interrupt the operation of said carriage shifting mechanism at the conclusion of any cycle of operation thereof, holding means for preventing operation of said spring means, means selectively adjustable to form a mechanical representation corresponding to any of the respective operating positions of said carriage, and means jointly controlled by the carriage and said selectively adjustable means for releasing said spring means from the restraint of said holding means.

HAROLD T. AVERY.
